CLOTHES WRINGER

Henry Dreyfuss, New York, N. Y., assignor to The Hoover Company, North Canton, Ohio, a corporation of Ohio

Application February 29, 1952, Serial No. 18,736
In Great Britain August 31, 1951

Term of patent 14 years

(Cl. D49—1)

To all whom it may concern:

Be it known that I, Henry Dreyfuss, a citizen of the United States, residing at New York city, in the county of New York and State of New York, have invented a new, original, and ornamental Design for a Clothes Wringer, of which the following is a specification, reference being had to the accompanying drawings, forming a part thereof.

In the drawings:

I claim:

The ornamental design for a clothes wringer, substantially as shown.

HENRY DREYFUSS.
